INVENTOR.
Walter A. Tratsch
BY Clarence E. Thruy,
His Attorney.

UNITED STATES PATENT OFFICE

2,550,887

ELECTRIC PELLET PROJECTING PISTOL

Walter A. Tratsch, Chicago, Ill., assignor to Clarence E. Threedy, Chicago, Ill., as trustee

Application October 28, 1947, Serial No. 782,540

1 Claim. (Cl. 124—1)

1

This invention relates to certain new and useful improvements in electric pellet projecting pistols and has for its principal object the provision of an improved construction of this character wherein there is embodied electrically operated mechanism for moving a shot or ball propelling plunger rapidly whereby to project a ball or shot with the maximum of speed.

Among the several objects of the invention is the provision of a target practicing pistol which is simple in construction, easy of operation, and positive in performance.

Yet another and equally important object of the invention is to provide in a target practicing pistol electrically operated means or mechanism, for shot propulsion, synchronized with an electrically operated shot delivering means, all actuated by the simple operation of a trigger.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is an interior side elevational view of the pistol embodying my invention;

Fig. 2 is a fragmentary side view of the reverse side of the pistol as shown in Fig. 1;

Fig. 3 is a fragmentary side elevational view similar to Fig. 1 but showing the parts in different positions;

Fig. 4 is a fragmentary sectional detail view similar to Fig. 2 but showing the parts in different positions; and

Fig. 5 is a suggested wiring diagram proposed to be employed in the invention.

The several objects of my invention are accomplished by the preferred form of construction shown in the accompanying drawings and by which construction it is proposed to deliver a shot or ball to the firing tube just prior to the operation of the shot propelling plunger so that each time the plunger is moved toward firing position there will be present in the firing tube a shot or ball for propulsion.

In Fig. 1 of the drawing a block is indicated at 10 and in this block there is formed a shot delivery passage 11 which communicates with a firing tube 12 forwardly of the plunger tube 13. Communicating with the delivery passage 11 is a feed tube 14. Adapted for movement into this passage is a feed plunger 15 formed as a part of a solenoid rod 16 operating within a magnetic solenoid coil 17.

2

The rod 16 has a head 18 which limits its upward movement and serves by reason of its weight to move the rod 16 downward from shot lifting position after de-energization of the coil 17. The downward movement of the rod 16 is limited by a stop bar 19 secured to the bracket 20 which supports the coil 17 from the block 10.

The shot propulsion plunger is indicated at 21 and comprises a solenoid rod movable within a magnetic coil 22. This rod 21 has a head 23 formed thereon and attached to this head as at 24 is one end portion of a return spring 25, the opposite end portion of the spring 25 being connected as at 26 to a mounting plate 27 shaped for enclosure within the handle portion 28 shown in dotted lines. This plate 27 may be secured to the flange 29 of the coil 22, as at 30.

Pivotedly connected to the plate 27 as at 31 is a trigger 32. This trigger 32 is provided with an integral lifting finger 33 adapted to engage beneath a pin 34.

This pin 34 is carried by an actuating arm 35 having one end portion provided with an elongated slot 36 through which projects the shank of a screw 37 relative to which the actuating arm 35 is longitudinally movable and pivotally connected to the plate 27.

This actuating arm 35 has a switch-engaging head 38 formed at its upper end portion, the head being provided with an offset portion 39 for reasons hereinafter set forth.

Carried by the plate 27 is a switch structure 40 comprising spaced contact fingers 41 and 42. An actuating plate 43 is provided and this plate has connection with the finger 41 by an over-throw spring 44 which spring serves to flex the plate 43 on opposite sides of its long axis. The end portion 45 of the actuating plate 43 is adapted to be engaged by the offset portion 39 of the head 38 when the actuating arm 35 is moved upwardly in a manner hereinafter described. The actuating arm 35 is normally held with the head 38 thereof in contact with the actuating plate 43 by means of a spring 46 having one end connected to the arm 35 as at 47 and the opposite end portion connected to the plate 27 as at 48.

Rotatably carried by the plate 27 is a ratchet wheel 49 and adapted to engage this ratchet wheel 49 is a detent 50 pivotally carried by the plate 27 as at 51.

A solenoid coil 52 is carried by the plate 27 and the rod 53 thereof has connection with the detent 50 whereby to disengage the detent 50 from the ratchet wheel 49, the rod 53 being normally urged outwardly of the coil 52 by a

spring 54. A pin 51' is carried by the wheel 49 and to this pin 51' is connected one end portion of a spring 52', the opposite end portion of the spring 52' being connected to the pivot pin 55 supporting the wheel 49, the arrangement being such that rotation of the wheel 49 in an anti-clockwise direction will tension the spring so that when the wheel 49 is released by the detent 50, it will rotate under action of the spring 52' to normal starting position. This pin 51' also serves to limit the anti-clockwise rotation of the wheel 49.

In the wheel 49 are formed a plurality of threaded openings 56 into any one of which is adapted to be threaded a stop pin 57 to limit the clockwise rotation of the wheel 49. This arrangement limits the number of shots to which the player is entitled.

The trigger 32 has pivoted thereto as at 58, an arm 59 the end of which is adapted to engage the wheel 49 to rotate the wheel step by step each time the trigger 32 is pivoted under the pressure of the trigger finger of the hand. This arm 59 has spring connection with the finger 33 by means of a spring 68 and is limited in its downward pivotal movement by a stop pin 61 carried by the plate 27. The pin 51' and limiting pin 57 are adapted to cooperate with the plate 62 carried by the plate 27 to limit the rotation of the wheel 49.

On the plate 27, on the reverse side thereof, as viewed in Fig. 2, there is mounted a switch structure 63 comprising a pair of spring contact fingers 64 and 65. Adapted to bear against the finger 64 is a pin 66 carried by the actuating arm 35.

In Fig. 5 a coin controlled switch is diagrammatically indicated at 67. This switch 67 controls the circuit to the coil 52 and until this coil 52 is energized, the detent 50 will hold the wheel 49 against clockwise rotation with the result that the trigger will be blocked when the pin 51' engages a plate 62 against movement by engagement of the arm 59 with the wheel 49. Upon energization of the coil 52, the wheel 49 will return to starting position and the trigger 32 will be free to pivot under finger pressure. Pivotal movement of this trigger under finger pressure in an anti-clockwise direction as viewed in Fig. 1 will initially move the actuating arm 35 upwardly as viewed in Fig. 1 to move the actuating plate 43 to a position where the overthrow spring 44 will move the contact finger 41 into engagement with the contact finger 42 whereupon the coil 17 will be energized and move the solenoid rod 16 upwardly to a position where the shot or ball B will enter the plunger tube 13 and roll to a position X, Fig. 1, in a position to be engaged by the propulsion plunger 21 the gun being tilted slightly upwardly to cause the shot to roll by gravity to such position.

As the arm 35 continues its upward movement, the pressure of the pin 66 against the end portion of the contact finger 64 will move the same into contact with the contact finger 65 whereby to energize the coil 22 to move the propulsion plunger 21 in firing direction with respect to the tube 12. The final upward movement of the actuating arm 35 will cause the offset portion 39 to be disengaged from the actuating plate 43

allowing this plate 43 to return to its initial position during which the overthrow spring 44 will disengage the finger 41 from the finger 42 to de-energize the coil 17. Return of the actuating arm 35 to its initial position will dis-engage the contact finger 64 from the finger 65 to de-energize the coil 22.

Upon conclusion of a predetermined number of shots, the pin 51' will have been moved into engagement with the plate 62 and will block the trigger against operation until the coil 52 is again energized.

Suitable means may be provided at the mouth of the feed tube 14 to prevent the balls or shots from accidentally dropping therefrom. This means may be in the form of a spring leaf 14' attached to the tube 14 as shown in Fig. 1 with an end portion thereof yieldably projecting into the path of movement of shots or balls.

From the foregoing description it will be apparent that I have provided a target practicing pistol which is entirely electrically operated; that a simple and effective means is provided for delivering a ball or shot to the firing tube just prior to the movement of the propulsion plunger 21. In this firing tube at the point X may be provided a leaf spring 12' similar to the spring 16' to prevent accidental rolling of the ball or shot from the tube 12.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claim.

Having thus described our invention, what I claim as new and desire to protect by Letters Patent is:

A target practicing pistol comprising a firing tube, a shot feeding tube communicating with the firing tube, magnetically actuated means including a coil and a plunger, the latter engageable with a shot substantially adjacent the point of communication between the feeding tube and the firing tube for delivering a shot to a firing position in the firing tube from the feeding tube, magnetically actuated means including a coil and a plunger, the latter movable into the firing tube to engage a shot delivered thereto by the plunger of the first named magnetically actuated means, for projecting said shot from said firing position within said firing tube, and trigger actuated means for successively energizing the coils of said magnetically actuated shot delivering means and said magnetically actuated shot firing means.
